BACON DRAINING RACK OR SIMILAR ARTICLE

Robert C. Browne, Charlotte, N. C.

Application September 21, 1956, Serial No. 43,025

Term of patent 14 years

(Cl. D44—1)

Figure 1 is a top perspective view of a bacon draining rack or similar article showing my new design; and

Figure 2 is a bottom perspective view thereof looking up at the opposite side from that shown in Figure 1.

The design is characterized by the stepped relation of the grid portion relative to the base.

I claim:

The ornamental design for a bacon draining rack or similar article, substantially as shown and described.
